UNITED STATES PATENT OFFICE.

DAVID WILSON, OF RICCARTON, LINLITHGOW, SCOTLAND.

POTATO CLEANING AND SIZING MACHINE.

No. 851,466.

Specification of Letters Patent.

Patented April 23, 1907.

Application filed January 8, 1904. Serial No. 188,197.

To all whom it may concern:

Be it known that I, DAVID WILSON, a subject of the King of the United Kingdom of Great Britain and Ireland, and a resident of Riccarton, Linlithgow, Scotland, farmer, have invented new and useful Improvements in Potato Cleaning and Sizing Machines, of which the following is a specification.

The object of this invention is to provide a machine for cleaning and sorting potatoes, etc., and consists in first removing particles of soil adhering to the potatoes, sorting the potatoes according to size and then discharging the assorted potatoes into suitable receptacles.

Figure 1 is a side elevation. Fig. 2 an end view of the right hand side of Fig. 1. Fig. 3 is a cross section of the revolving separating screen. Fig. 4 a part plan of the riddle and traveling table or conveyor. Fig. 5 shows a section of the table in detail.

I employ an elongated separating screen A hexagonal shaped as shown in Fig. 3 and which is capable of being rotated on an axle B which is slightly inclined as seen in Fig. 1. Below the one or lower end of the inclined separating screen is an endless travelling table C, travelling at right angles to the rotating separating screen, as shown by the arrows Fig. 2; the travelling table being formed of parallel laths D Fig. 5 of say galvanized iron and which are riveted to the driving chains C⁷.

The potatoes are fed into the upper end of the separating screen A by means of a hopper (not shown). As the separating screen is revolved the earth and small potatoes escape through the smaller meshes of that end of the separating screen and on to the inclined wired riddle A¹ Fig. 1, below, by which they are further separated from the earth, the small potatoes thus cleaned rolling down the inclined riddle A¹ into a basket below. The intermediate sized potatoes pass on along the separating screen until they arrive at about the centre of the length of the separating screen, where the separating screen is of larger meshes, which allows the intermediate sized potatoes to fall through on to the travelling table C.

The board G, Figs. 1 and 5 divides the length of the travelling table into two portions C⁸, C⁹, so that the said intermediate sized potatoes in dropping through the por-

tion a⁴ of the revolving separating screen fall on to the one half portion C⁸ of the travelling table; see Fig. 4 which is a part plan of the separating screen and of the travelling table. The larger potatoes pass out of the open end of the separating screen on to the other portion C⁹ of the travelling table Fig. 4. Thus there are two streams of different sized potatoes being continuously discharged from the end of the travelling table, as hereinafter more particularly referred to. Fig. 4 shows four of the laths D of the endless travelling table and which are riveted on to the endless driving chains C⁷ and also shows the division G of the table.

The frame a¹ of the machine is preferably constructed of wooden spars; the whole apparatus being carried by the four wheels a² two at each side, so that the machine is portable.

a⁵ is a board fixed across the side of the machine and which assists in giving rigidity to the frame work of the machine.

The elongated hexagonal shaped separating screen is supported by the arms B¹, Fig. 3, the said arms being mounted on the axle 80 B, the axle being carried in bearings at each end of the machine.

The riddle A is rotated by means of the wheel b which may be driven by hand or any other suitable power. Motion to the endless 85 travelling table C is effected by the sprocket wheels c, c¹ Figs. 1 and 2 which are mounted on the shaft c² which is rotated by the sprocket chain F passing over the sprocket wheels E, D.

One end of the travelling table C is elevated as shown in Fig. 2 for the purpose of discharging the two streams of potatoes into sacks through the depending chute portion C⁴.

The end of the table frame C¹ is provided with the hinged doors C⁵ so that when the potato bags are filled, and being removed, the potatoes are prevented from dropping out of the end by closing the doors.

To fill baskets instead of sacks the elevated portion of the travelling table may be dispensed with, the depending discharge orifice C⁴ with door C⁵ being fitted to the end of the straight portion of the frame of the travelling table.

In order to carry the potatoes up the inclined portion C³ of the travelling table, I

form every alternate lath with a projection *d*, as shown in Fig. 5 which is an enlarged section of Fig. 4 on line 1, 2.

The elevated end of the travelling table C Fig. 2 passes round the upper sprocket wheel C², the bend of the travelling table being guided by sprocket wheel C³, the top of the travelling table being held down on to the top of the said sprocket wheel by means of flanges *e* secured at each side of the frame work of the elevator, a portion of the ends of the raised portion *d* of each alternate lath D being cut away to allow the laths to pass the said projecting flanges *e* of the elevator frame.

The frame C¹ of the table C may for convenience in transit be turned up on its hinges at C⁴ as shown in Fig. 2.

I do not limit myself to the exact construction shown and described herein for cleaning and sorting potatoes, etc., but the same may be varied to be adapted for the

sorting of sand, gravel, etc., without departing from the spirit of my invention.

Claim

In a potato cleaning and sizing machine, the combination of a supporting framework, a separating screen consisting of a series of graduated screens mounted on a shaft therein said shaft being directly connected to a driving wheel, a riddle mounted beneath one portion of said separating screen, a divided conveying table mounted beneath the other portion of said separating screen said table receiving motion through the medium of a chain and sprocket connection from a suitable driving wheel, an elevated chute having a discharge opening at its highest part, and doors adapted to close said chute.

DAVID WILSON.
